LIFESAVING DEVICE

Henry W. Walters, Jacksonville, Fla.

Application September 12, 1935, Serial No. 40,311

3 Claims.

(Cl. 9—14)

This invention relates to life saving apparatus, and among other objects, aims to provide an improved buoy so constructed that an exhausted or nearly drowned person may be supported 5 thereby without the possibility of being washed away by a wave or slipping off from sheer exhaustion. The invention has more specific objects which will be understood from the following description of a preferred embodiment 10 thereof.

In the accompanying drawing forming a part of this specification:—

Fig. 1 is a plan view of one form of life saving apparatus made in accordance with the invention; and

Fig. 2 is a plan view of another form.

Referring particularly to the drawing, there is shown in Fig. 1 a hollow buoy 5, preferably elongated, with pointed ends, which may be 20 identical in construction with the buoy disclosed in my co-pending application, Serial No. 683,686 filed August 4, 1933, or which may be of a different construction. The only essential is that the buoy be capable of sustaining the weight of 25 a human body submerged in water, and it is preferred that it be shaped, as shown, to facilitate towing it through water, especially water disturbed by breakers or travelling waves.

The buoy 5 has eye-bolts 6 at either end and 30 has loops or eyes 7 intermediate its ends, and a tarred rope 8 is run through the eyes, as shown, and may then be spliced so as to be endless, to provide means which a bather may grasp to receive support from the buoy. The rope 8 35 also aids towing of the buoy by a life-guard.

A rope 9 is passed through one of the eyes 6 and has snap buckles 10 on its ends. Floats 11 are adjacent the snaps 10, so as to overcome the 40 weighting effect of the snaps, thus insuring that the ends with the snaps (which are commonly free of the rope 9) will not sink in water and hence will be in sight at all times to permit quick 45 grasping and snapping of the buckles on rope 9, as shown. Buoyant toggles 12 are also carried 50 on rope 9 in such a way that loops 9a are formed, and as the lengths of rope 9 which pass through toggles 12 are frictionally held within the toggles, said loops 9a may be enlarged to any extent permitted by the length of rope 9. Obviously each 55 toggle 12 forms two loops, when the corresponding snap buckle 10 is engaged with rope 9.

Attached preferably to the same eye 6 that receives rope 9, but in some cases to the eye at the other end of the buoy, is a rope 13 having a toggle 14 and a looped end 13a carrying said toggle.

The toggles 12 and 14 are buoyant, so as to support the ropes in water, but they are preferably adjustable to insure a tight frictional grip at all times on the ropes, even after the latter are weather-beaten.

In the form of Fig. 2, the same buoy 5 is used, with eyes 6 and 7 and a rope 8 strung about its sides and ends. Also the end rope 13 with its loop 13a and toggle 14 is secured to one of the eyes 6 at one end of the buoy, all as in the form 10 of Fig. 1.

Attached to either side of buoy 5 is a rope 15 having snap buckles 16 on its ends, securing it to the rope 8. Floats 17 are adjacent each snap buckle 16, and support the ends of rope 15 on the 15 surface of the water. The rope is doubled as at 15a and the two lengths of the rope are passed through a buoyant toggle 18, which frictionally 20 grips the rope; and when the snap buckles 16 are engaged with rope 15 as shown, said rope forms two loops at one side of the buoy 5.

On the other side of the buoy there is a second rope 15 which may be arranged as already described, but which is shown arranged differently to illustrate the possibilities of the apparatus. Here the rope has both ends engaged by means of 25 snap buckles 16 with the loop 15a, thus creating a double loop at the side of the buoy.

The uses and advantages of the described apparatus when effecting rescues of drowning persons at beaches, etc., will be fairly obvious. The 30 rope 13 is useful for towing the buoy, as the loop 13a may be laid over the shoulder or around the neck of the life-guard, who may then swim with arms and legs unimpeded. The loops formed by 35 ropes 9 and 15 may be placed around the chest and shoulders of an exhausted or half-drowned bather, and he will be supported while the rescuer goes to the relief of others, or until the buoy is 40 towed to the shore. Each loop of rope 9 may support one body, or the two loops together may be secured more or less tightly about the shoulders and upper arms of the person in distress, the toggles 12 permitting adjustment of the loops to 45 grip the limbs as snugly as desired. The loops formed by ropes 9 and 15 may also receive the legs of the bather, and his weight will then be supported from a lower point, making it somewhat easier for him to swim with the towed buoy. The device prevents the loss of a half-drowned 50 person while struggling through surf with a strong undertow, and will make possible many rescues which cannot be effected by the strongest swimmers.

Obviously the present invention may be em- 55

bodied in several forms neither shown nor described.

Having described two forms of the invention, what I claim as new and desire to secure by Letters Patent is:—

- 5 1. Life saving apparatus comprising, in combination, a buoy; a rope secured to the buoy and extending around the sides and ends thereof; and another rope having snap buckles on and intermediate its ends to connect it with the rope on the buoy and having a toggle slidible on the rope on opposite sides of the intermediate buckle to adjust the loops formed in said rope by said buckles.
- 10 2. Life saving apparatus comprising, in combination, a buoy; a rope secured to one side of the

buoy; and another rope having a toggle intermediate its ends and forming a loop; means to attach said loop to the buoy rope; and means on the ends of the second named rope to attach said ends quickly to the loop or to the buoy rope. 5

3. Life saving apparatus comprising, in combination, a buoy; means attached to the buoy by which it may be towed; a rope loosely attached to one end of the buoy and having snap buckles on each end; the loosely attached rope being provided with two buoyant slidible toggles through each of which are passed two lengths of said rope, each toggle providing two loops when the ends of said rope are attached to the rope by means of said snap buckles. 10
